TOY VEHICLE

James B. Fisher, Waukesha, Wis.

Application April 26, 1946, Serial No. 128,975

Term of patent 14 years

(Cl. D34—15)

To all whom it may concern:

Be it known that I, James B. Fisher, a citizen of the United States, residing at Box 795, Route 4, Waukesha, in the county of Waukesha and State of Wisconsin, have invented a new, original, and ornamental Design for a Toy Vehicle, of which the following is a specification, reference being had to the accompanying drawing, forming a part thereof.

In the drawings:

Figures 2, 3, 4 and 5 are, respectively, rear, front, top and side views thereof.

I claim:

The ornamental design for a toy vehicle, substantially as shown.

JAMES B. FISHER.
